UNITED STATES PATENT OFFICE

2,512,808

EARTH AUGER AND GROOVER

Herman W. Nissen, Pipestone, Minn.

Application January 28, 1947, Serial No. 724,758

1 Claim. (Cl. 255—65)

1

This invention relates generally to manually operated earth boring augers, and more particularly to an earth auger having a groover incorporated therewith whereby a laterally disposed groove or undercut is formed, to facilitate the formation of laterally extending shoulder portions in a mass of concrete placed in the hole to anchor the lower end of a post.

It is well understood that the use of concrete to anchor the lower ends of posts in post holes is not new, nor is it new to provide undercuts in the bored hole to form shoulders on the concrete mass, the present invention residing in improved means, in combination with an earth auger, to form this undercut in a more expeditious manner.

It is an object of this invention, therefore, to provide an earth auger with a grooving device which can be incorporated with the auger and adjusted to operative or inoperative position by a manual control positioned on the handle portion of the auger.

Another object of this invention is to provide a device of this character with manual control means whereby the depth of the undercut may be conveniently regulated.

A still further object of this invention is to provide a device of this character with an improved form of undercutting blades.

A still further object is to provide a device of this character which is not unduly heavy or unwieldy.

And a last object to be specifically mentioned is to provide a combined tool of this character which is inexpensive and practicable to manufacture, extremely simple to use, and which is of sufficiently sturdy construction to provide for generally efficient and durable service.

With these and other objects definitely in view, this invention resides in certain novel features of construction, combination and arrangement of parts and portions as will be hereinafter described in detail and particularly set forth in the appended claim, reference being had to the accompanying drawings which form a material part of this application, and in which:

Figure 1 is a side elevational view of the assembled tool, the handle portions being broken and fore-shortened to conserve space;

Figure 2 is an enlarged fragmentary detail view of the upper portion of the handle and the manual groover control;

Figure 3 is a fragmentary view of a post anchored according to this invention in a mass of concrete;

2

Figure 4 is an enlarged fragmentary detail view of the lower portion of the auger and groover, and representing the same structure as that shown in Figure 1 but turned through an angle of 90 degrees about the vertical axis of the tool;

Figure 5 is an elevational view of the auger and groover in a hole bored in the earth by the auger and with the groover retracted or in inoperative position, and

Figure 6 is a fragmentary view of the lower end of this device with the auger blades removed and a bucket member secured in the place thereof, to facilitate the removal of the loose earth displaced by the groover.

Similar characters of reference designate similar or identical parts and portions throughout the specification and throughout the several views of the drawings.

Referring now to the drawings in detail, it will be noted that this invention includes an elongated shaft 10 having a T-member 12 and a cross-handle 14 at the upper end of said shaft and adapted to be grasped by the hands of the operator. The lower end of the handle 10 is equipped with a metal ferrule member 16, having diametrically disposed supporting flanges 18, and a sliding cross arm 20 having a depending portion 22 terminating in an attachment flange 24 whereon an auger blade 26 is secured according to conventional practice. This blade is arcuate at the lower end and may be sharpened and bifurcated as indicated at 28.

A similar blade 30 may be similarly secured to the depending portion 32 of a cross arm 34. In order that the auger be made adjustable as to effective diameter the cross arms 20 and 34 are slidably mounted on the lower portion 36 of the flanged member 18, this member 36 being centrally apertured and the arms 20 and 34 each having a plurality of spaced apertures 38 to allow the insertion of a bolt 40, the drawings illustrating an auger adjustable to three different diameters.

The groover mechanism is mounted on an attachment plate 42 which is firmly mounted on the shaft 10 by means of a pair of U-bolts 44 and 46, the lower U-bolt 46 being positioned on the shaft 10 so as to abut the upper end of the ferrule member 16, this upper end being preferably formed with a collar 48. The attachment plate 42 has a pair of parallel flange plates 50 and 52 designed to define a channel for the slidable mounting therein of the groover plate 54 which is generally rectangular but provided with an acute angled upper

corner 56. Formation of the cutter blade with a sharpened corner 56 has been found to facilitate the actual cutting of the groove in the earth and has the added advantage that it provides for a concrete anchoring mass having maximum anchoring utility with a minimum volume of concrete used in the formation of the shoulder portions of this concrete anchoring mass. The theory of the shaping of the grooving blade 54 is carried out in the formation of the channel forming flanges 50 and 52 by making the upper flange plate 50 longer than the lower flange plate 52, in order that the extended corner 56 of the groover blade be given maximum support.

Linear deformations which may take the form of a rack or row of spaced apertures 53 are formed in the groover plate 54 and are adapted to register with the pinion 60, the teeth of which are arculate in order that they may be self-cleaning and will not become clogged with earth and in order that the teeth will coact with the groover plate and flanges 52 and 54 to prevent binding. This pinion 60 is secured by a set screw 62 to the lower end of a shaft 64, disposed in spaced parallel relation with the shaft 10 and secured at the lower end thereof in a bearing member 66, which may be integral with or supported on a flange 68 on the member 52. A key 70 may be provided in the lower end of the shaft 64 to further secure this portion of the assembly.

The upper end of the shaft 64 is mounted in an apertured flange 72 secured by a U-bolt 74 to the shaft 10; and a hand-wheel 76 is secured by a nut 78 on the upper end of the shaft 64, to provide for the manual control of the shaft 64. The hand-wheel 76 may be further secured against rotation relative to the shaft 64 by a transversely disposed key 80, as indicated in Figure 2. The lower end of the hand-wheel 76 is provided with ratchet teeth 82, and a spring loaded locking key 84 is mounted in a sleeve 86 which may be integrally formed on the upper portion of the angle flange plate 72, the inner end of the locking key 84 being adapted to engage the teeth 82 to retain the shaft 64 against rotation after the required adjustment thereof has been made.

The operation of this device will be obvious from a consideration of the foregoing description of the mechanical details thereof, but if reference be now had to Figure 3 it may be well to note that a hole 88 is first bored in the earth 90 to the desired depth, after which the hand-wheel 76 is turned with the locking key 84 released, to extend the grooving blade 54, and the tool is again rotatively operated to cut a groove 92 laterally of the hole 88. The hand-wheel 76 will, of course, be gradually turned in order that the blade 54 can be progressively extended until a groove of sufficient depth has been formed. If preferred, a bucket formed in two sections 94 and 96, as illustrated in Figure 6, may be used to gather the loosened earth resulting from the formation of the groove 92. These complementary sections 94

and 96 may be secured to attaching flanges 24 in the same manner as the auger blades 26 and 30, and it is preferred that the bottom portions 98 should be substantially flat and, of course, semi-circular, and it will be noted that the section 94 is made of a greater diameter than the section 96 to fit over the latter and allow for adjustment as to size of the bucket member, in the same manner as the auger is adjusted as to effective diameter. 10 When the loosened earth has been removed, a mass of semi-fluid concrete is poured into the hole 88, and the end of the post 100, preferably notched as at 102 is inserted into the semi-fluid concrete which will take the angular form shown at 104. 15 Another method entails less difficulty in the insertion of the post 100 and comprises an alteration in the order of procedure in which the post 100 is first placed in the hole 88 and the semi-fluid concrete is then poured into the hole. In either case the concrete will be made to completely fill the groove 92 and to surround the lower end portion of the post 100 and on hardening will provide secure anchorage for this post.

Though there has been shown a particular embodiment of this invention, this application is not limited to this particular embodiment, but it is desired to include in the scope of this invention the construction, combination and arrangement of parts and portions substantially as set forth in the appended claim.

Having thus described my invention what is claimed as new and desired to be secured by Letters Patent is:

The combination of an earth auger having a shaft, cutting blades and a handle, with a groover mechanism comprising a channeled guide member having upper and lower flange plates perpendicularly secured to said shaft above said blades, a groover plate slidably mounted in said guide and having horizontally aligned apertures defining a rack, a second shaft rotatably mounted on said guide at its lower end and on said auger shaft at its upper end; a hand wheel on the upper end of said second shaft adjacent said handle, and a pinion secured to the lower end of said second shaft and having teeth with substantially semi-circular vertical faces to lessen the binding of said groover plate in said guide and engaging said rack, whereby said groover plate may be moved laterally.

HERMAN W. NISSEN.
